HYDRAULIC TIMING MECHANISM

Ralph E. Price, Highfield, Md., assignor to Landis Tool Company, Waynesboro, Pa.

Original application February 28, 1940, Serial No. 321,310, now Patent No. 2,335,356, dated November 30, 1943. Divided and this application April 25, 1941, Serial No. 390,433.

1 Claim. (CL. 60—52)

This invention is a division of Price et al. application Serial No. 321,310, filed February 28, 1940, now Patent No. 2,335,356, granted November 30, 1943, and relates to timing mechanisms, particularly of the hydraulically operated type.

It is an object of this invention to provide a timing mechanism which will be simple in construction and operation and inexpensive.

A further object is to provide a timing mechanism which is capable of an infinite number of variations.

A further object is to reset the timing mechanism after it has completed its function.

Figure 1 is an end elevation of a machine partly in section.

Figure 2 is a sectional plan view of my invention.

Figure 3 is a piping diagram showing an application of my timer.

In order to control hydraulically actuated movements by a timing mechanism it is essential that the mechanism function at a uniform rate under all conditions of temperature, otherwise in a given time it will move at one rate and thru a given distance if the hydraulic medium is cold and at a different rate and thru a different distance if the medium is warm. If the timing device is to be operated hydraulically it is obviously important that it must function at a uniform rate at all times.

In order to assure such operation, use is made of a relief valve which is described and claimed in my copending application Serial No. 390,432, filed April 25, 1941, for Relief valve. Briefly it consists of a differential piston 130 in a cylinder 134. One end of said piston is subjected to a pressure determined by throttle valve 138, and the other end to a pressure determined by the resistance offered by the driven part or parts. The large portion of said piston controls an exhaust passage Z thru which excess fluid may escape. The effect of this device on a hydraulic system is that the driven parts all function at a uniform rate regardless of the temperature of the fluid. The valve 130 maintains constant flow regardless of viscosity because it is actuated by fluid under pressure instead of by a spring. The pressure of the fluid varies with viscosity and therefore the setting of the relief valve also changes and instead of a change in flow the flow remains constant. For further details concerning the operation of this device, reference is made to the above mentioned co-pending application Serial No. 390,432.

In Figure 1, my invention is shown as applied

to the wheel feed mechanism of the parent application. Numeral 10 indicates the bed of a grinding machine, 11 a work carriage slidably mounted thereon, 12 a swivel table mounted for angular adjustment on said carriage, 13 a headstock, and 14 a footstock, both mounted on said table. Any suitable driving device on the headstock serves to rotate the work piece. Carriage 11 may be shifted manually by means of handwheel 18 thru suitable mechanism, not shown. When actuated by power the direction of movement of the carriage is controlled by a reversing lever 19 actuated by dogs 20 and 21 on dog rack 22. A wheel base 25 having a grinding wheel 26 rotatably mounted thereon is slidably mounted on the bed 10 for movement toward and from the work carriage. A cover member 27 hinged for easy inspection encloses the wheel base and grinding wheel and has a separate compartment therein for each of said parts. A handwheel 28 provides a manual means for shifting said wheel base toward and from the work. The means for shifting said wheel base by power consists briefly of a piston 46 in a cylinder 47. Fluid under pressure is directed to one side or the other of said cylinder thru lines 84 or 86 by a valve 80 which may be shifted in one direction by fluid under pressure applied thru line 113, and in the opposite direction by a spring 76.

The fluid under pressure for shifting said valve 80 is supplied thru line 113 by a timing valve shown in Figures 2 and 3. Said valve consists in the valve member 100 slidably mounted in a bore 101 in cylindrical housing 102, sometimes referred to hereafter as a timer. One end 103 of said valve is smaller in diameter than the rest of the valve and fits in a bore 104 of corresponding diameter formed in a member 105 inserted in bore 101. The portion of said valve which may be acted on by fluid under pressure in lines 114 and 115 is therefore smaller than the opposite end thereof. An end plate 106 has a line 107 therein leading to bore 104. Another end plate 108 has a line 109 therein leading to bore 101. On one side of housing 102 are two lines 110 and 111 located toward the right hand end of the valve. In the position of valve 100 shown, line 111 is connected thru peripheral groove 112 of valve 100 with a line 113 on the opposite side of said housing. On said opposite side but toward the left end of the valve are two additional lines 114 and 115. Said lines are connected by a passage 116 in which is located a ball check valve which permits passage of fluid from lines 114 to 115. Valve 100 has a closed bore forming a passage 117 which

is connected to the chamber at the left end of bore 101 thru a port 118. Spaced axially from said port is a second port 119 joining said bore 101 and passage 117 thru a peripheral groove 120. Said groove forms a chamber between said valve and said bore 101. Movement of valve 100 to the left is retarded by the fluid exhausting from the bore 101 thru line 115 and thru a throttle valve 121 in said line. When the valve 100 moves to a point where port 119 coincides with line 114, the fluid may be released thru passage 117, passage 116, port 118 in said valve, and exhaust line 114 in the housing, thus permitting said valve to move quickly to reverse position.

Operation

Fluid under pressure directed by valve 308 thru lines 420 and 421 passes first thru a hydraulic timer 102. Part of said fluid passes from line 421 thru line 109 to shift the valve member 100 from right to left. Another part of said fluid passes from said line 421 thru line 111 and peripheral groove 112 of valve 100 thru line 113 to shift feed valve 80 to operative position and hold it there for a predetermined time. Movement of valve 100 from right to left is controlled by the fluid being forced out thru line 115 and thru throttle valve 121 into line 114 against pump pressure since the exposed area of the left end of said valve is less than that of the right end. When valve 100 opens line 114 thru peripheral groove 120, passage 117, and ports 118 and 119 to bore 101, further movement is uncontrolled and said valve moves rapidly to the extreme left hand position. Line 111 is blocked by valve 100 and line 113 is connected by peripheral groove 112 of valve 100 to exhaust line 110 which allows valve 80 to be returned by spring 76 to its original position. In order to reset valve 100, lever 324 must be shifted so that valve 308 will connect line 421 with an 40 exhaust outlet. Said lever may be shifted man-

ually or automatically by power controlled by said timing valve. Fluid under pressure in line 114 will shift valve 100 to the right when line 421 is connected to an exhaust outlet as described above. If it is desired to stop the grinding operation before the end of the cycle, the operator can by shifting lever 324 open line 421 to exhaust so that fluid under pressure in line 115 will shift valve 100 to the right. Line 111 which is connected to line 421 will also be opened to exhaust. Line 111 being connected thru line 113 to reversing valve 80 will permit the exhaust of fluid therefrom. Spring 76 may then reset said reversing valve to direct fluid under pressure to withdraw the wheel support.

15 I claim:

A hydraulic system for machine tools including a pump, a motor for shifting a tool carriage toward and from operative position, a reversing valve for said motor, said valve being normally held in position for shifting said motor in one direction, a pressure operated valve for directing fluid under pressure to actuate said reversing valve away from normal position and thus to cause said tool carriage to move to operative position, a by-pass relief valve adapted to compensate for variation in viscosity in the hydraulic medium whereby to insure uniform operation of all mechanisms in the system regardless of the viscosity of the fluid, said pressure operated valve being constructed to deliver fluid under pressure to said reversing valve for a period dependent on the rate of movement of said pressure operated valve and thereafter, to cut off the flow of fluid under pressure thereto and to connect said reversing valve with an exhaust line whereby said reversing valve may be returned to normal position and the tool carriage withdrawn from working position.

30 35 RALPH E. PRICE.
